UNITED STATES PATENT OFFICE.

GEORGE A. SEIB, OF ILION, NEW YORK, ASSIGNOR TO REMINGTON TYPEWRITER COMPANY, OF ILION, NEW YORK, A CORPORATION OF NEW YORK.

TYPEWRITING-MACHINE.

1,342,466.

Specification of Letters Patent.

Patented June 8, 1920.

Application filed December 6, 1918. Serial No. 265,512.

To all whom it may concern:

Be it known that I, GEORGE A. SEIB, citizen of the United States, and resident of Ilion, in the county of Herkimer and State 5 of New York, have invented certain new and useful Improvements in Typewriting-Machines of which the following is a specification.

My invention relates to typewriting machines and more particularly to carriage 10 controlling devices.

My invention has for its principal object to provide improved means for securing uniformity in the letter space position at 15 which the carriage comes to rest after it has been taken temporarily out of control of the escapement mechanism, as, for example, by operating the carriage release mechanism or by drawing the carriage back for 20 the beginning of a new line. For example, the margin stop is designed to arrest the carriage always at the same letter space position when it is drawn back to the right to begin a new line of writing, but under cer- 25 tain conditions and modes of operation of the machine the carriage will not come to rest at the usual and intended letter space position but will drop one step to the left, so that that particular line of writing will 30 be indented to the extent of one letter space. It is the purpose of my invention to improve the machine in respect to this particular fault and related faults.

To the above ends my invention consists 35 in certain features of construction and combinations and arrangements of parts all of which will be fully set forth herein and particularly pointed out in the claims.

In the accompanying drawings,

40 Figure 1 is a fragmentary rear elevation partly in section and showing the escapement and some associated parts of a Remington typewriter together with one embodiment of my invention.

45 Fig. 2 is a front to rear vertical sectional view showing my improvements.

Fig. 3 is a plan view showing the parts in the position they occupy when the carriage is moving toward the operator's right.

50 Fig. 4 is a view similar to part of Fig. 3 but with the carriage moving toward the operator's left.

Fig. 5 is a fragmentary enlarged view looking from the left-hand side of the machine and partly in section and illustrating

the engagement with and disengagement from the feed rack of a certain friction shoe.

Fig. 6 is a perspective view of the margin dog and some of its associated parts.

Figs. 7 and 8 illustrate a modified form 60 of the invention, the former being a plan view, and the latter an enlarged sectional view on the line $x-x$ of Fig. 7.

Fig. 9 is a front to rear sectional view of the machine, but with many parts thereof 65 omitted, the section being taken near the left-hand side of the machine.

In certain models of the Remington type- 70 writing machine the main frame includes a top plate 1 on which a bracket 2 is secured by means of a screw 3, said bracket having, as seen in plan view, a sort of yoke or bail shape; and an escapement wheel shaft 4, Figs. 2 and 3, is journaled at its ends in the forward and rear arms or branches of said 75 bracket 2, said shaft having an escapement wheel 5 rigidly mounted on its rear end. A sleeve 6 journaled on the shaft 4 has a feed pinion 7 rigid on or integral with its front end and at its rear end it carries a ratchet 80 wheel 8 which is engaged internally by a pawl pivoted to the forward face of the escapement wheel 5. The carriage 9 of the machine carries a feed rack 10 which en- 85 gages the pinion 7. Said feed rack is so mounted on the carriage that it can occupy the normal operative position shown in Fig. 2 or can be raised out of engagement with the pinion 7 to release the carriage, the raised position of the rack being shown in 90 full lines in Fig. 5, and the normal position by dotted lines in said figure. The carriage is drawn toward the operator's left by the usual main spring 11 coiled in a drum 11^a and connected with the carriage by a band 95 or tape 12. The construction is such that when the carriage is moving toward the left under the pull of the tape 12 the pawl and ratchet 8 constrain the escapement wheel 5 to turn with the sleeve 6, but when the car- 100 riage is pulled back toward the operator's right the ratchet wheel 8 can click idly over its pawl and the escapement wheel 5 can stand at rest; and also the carriage can be released from the escapement and moved in- 105 definitely in either direction without turning the escapement wheel by lifting the rack to the position shown in Fig. 5, out of engagement with the pinion 7. The escape- 110 ment wheel and feed pinion and associated

parts, are more fully shown and described in the patent to E. E. Barney, No. 1,270,918, dated July 2, 1918.

One form of dog rocker and feed dogs is shown in Fig. 1, these parts as well as the balance of the escapement mechanism being in most respects substantially as shown in my application for patent filed Sept. 6, 1916, Serial No. 118,607. In this escapement the dog rocker 13 comprises an upright part and right and left-hand trunnions, all made in one piece, said trunnions being pivoted on cone pivots 14 inserted in a bracket 63 that is secured to the under side of the top plate 1. The rigid dog 15 of this escapement is integral with the dog rocker 13 and the stepping dog 16 is pivoted to said dog rocker on a fore and aft pivot 17 and is capable of vibrating between the two stops 18 and 20. A light spring 19 is provided to throw the dog over against the stop 20 when it is not held by a tooth of the escapement wheel against the stop 18. The loose dog is normally in engagement with the escapement wheel and normally against the stop 18, as shown in Fig. 1. The dog rocker is vibrated by means of any suitable connections from the universal bar and space key acting through one or more pins or studs 21 on the lower end of an arm 22, which arm projects below the pivots 14, said arm being secured to the dog rocker by a screw 23 and adjustable by means of a screw 24, all in the manner more fully set forth in my pending application above referred to.

My invention, in the forms shown in Figs. 1 to 6, includes a third dog 25 in addition to the two dogs 15 and 16 that are mounted on the dog rocker. This third dog 25 I sometimes call a "margin dog" because one of its functions is to control the escapement in such a way as to insure an even left-hand margin to the writing. The dog 25 is in the nature of a bell crank including a horizontal arm lying in right and left-hand direction and terminating in a tooth 26 adapted to engage one of the teeth 27 of the escapement wheel 5. In the present instance, and preferably, the margin dog engages the same tooth 27 that is engaged by the feed dogs 15 and 16 or is in position to be engaged thereby, and which is accordingly sometimes called the "zero" tooth. The dog 25 is pivoted on a vertical, headed stud 28 secured at its lower end in a base plate 30 which in turn is secured to the top plate 1 by two screws 31 passing through elongated holes or slots in the plate 30; said slots providing for adjustment of said plate toward and from the escapement wheel. In order to provide a long pivot for the dog 25 said dog has an arm thereof bent up into a yoke piece 32 and again bent horizontally to form an ear 33 so that the

dog is pivoted on the stud 28 at two points spaced wide apart. A spring 34 coiled around the stud 28 tends to turn the dog 25 into engagement with the escapement wheel; that is to say, it tends to move the end of said dog toward the rear of the machine. The motion of the dog is limited in that direction by the escapement wheel itself and in the other direction by a pin 35 projecting from the base plate 30. 75

The dog 25 has a forwardly projecting arm 36 to which a spring friction shoe 37 is secured by rivets 38. This shoe may be made of spring metal lighter than the balance of the dog and its forward end 80 bent upward and thence forward into such position as to come into frictional contact with the under edge of the feed rack 10; and the contacting part of the shoe is enlarged and appropriately shaped to answer 85 its purpose. The manner of the engagement or contact of the shoe 37 with this rack 10 is indicated in Fig. 5 which in full lines shows the rack in its elevated or carriage-releasing position in which position the shoe 37 does not touch the rack; but when the rack drops down to its normal position shown in dotted lines it comes against the shoe 37, bending it down slightly and thus putting said shoe under 90 light spring tension against the rack. The spring shoe 37 is considerably stiffer than the spring 34, the latter being quite a light spring, with the result that when the carriage is at rest or is moving in letter space 100 direction as shown in Fig. 4, the friction of the rack 10 on the shoe 37 more than overcomes the spring 34 and retains the dog 25 out of engagement with the wheel; although during the return motion of the 105 carriage for the beginning of a new line, the spring 34 can and will move the dog 25 into engagement with the escapement wheel as shown in Figs. 3 and 6. Moreover, if the carriage be released from the escapement by raising the rack 10 the frictional contact between said rack and the shoe 37 is broken and the dog 25 is then free to be thrown into the wheel by the spring 34. Even when the carriage is drawn back 110 toward the right without raising the rack it is still the spring 34 that moves the dog into engagement rather than the friction of the shoe 37 because said spring acts much more quickly than the carriage. When said 115 carriage is started back toward the right therefore the rightward motion of the rack 10 permits the dog to move into the wheel rather than causes it to do so. If the spring 34 were eliminated then of course 120 the friction of the rack 10 on the shoe 37 would move the dog 25 into engagement with the escapement wheel on the return movement of the carriage and when the dog is kicked out then the friction keeps 125 130

it out of engagement on the forward movement of the carriage.

It will be perceived that whenever the carriage is pulled back toward the right and whenever said carriage is released the dog 25 immediately moves into engagement with a tooth 27 of the escapement wheel, locking said wheel against turning in letter feed direction; but it will also be understood that this dog must be moved out of engagement upon the first operation of the dog rocker after the carriage has been again restored to the control of the escapement. Otherwise even when the escapement was operated the carriage would be held by the dog 25. To this end said dog 25 is formed with a depending arm 40 and a device operated by the escapement mechanism is adapted to strike against this ear 40 and move the dog 25 toward the front of the machine out of engagement with the wheel 5. In the present instance said device consists of an adjustable screw 41 screwed through the upper part of the dog rocker. It will be perceived that this motion of the dog is effected both against the tension of the spring 34 and also against the friction between the shoe 37 and the rack 10, and that said friction will prevent the dog from coming back into engagement with the wheel. When the carriage is drawn back to begin a new line therefore, the dog 25 comes into action, but it is thrown out of action by the first operation of the dog rocker and it remains out of action as long as the writing operation continues in that line, coming into action again whenever the carriage is moved toward the right or is released from its escapement by the lifting of the rack.

40 A margin dog of the general sort here set forth has preferably associated therewith a detent dog to prevent backward turning of the escapement wheel at least beyond a certain fraction of a tooth space, and I have provided such a dog and mounted it on the same base plate 30 as my margin dog. Said base plate, which is here shown constructed of sheet metal, has a bracket 42 bent upward therefrom and, in order to prevent backward rotation of the escapement wheel, a gravity detent dog 43 is pivoted to said bracket on a horizontal stud 44 projecting toward the front of the machine from the bracket, said dog having ears 45 by which it is pivoted. The left-hand end of the dog 43, as viewed in Fig. 1, engages the second tooth 27 from the so-called "zero" tooth and said dog is prolonged toward the right in said figure to form a counter-balance 47, the weight of which restores the dog into engagement with the wheel. The downward motion of this counter-weight is conveniently limited by the upper end of the pivot 28 and the motion of the dog in the other direction is limited by a pin 46 projecting

forward from the bracket 42. Any other suitable form of detent can be employed but the one shown is effective and convenient especially as it is mounted on the same base as the margin dog so that this entire apparatus can be put on the machine and removed therefrom as a unit. With the two dogs 25 and 43 both in action it will be perceived that the escapement wheel is held in its proper position whether or not it is under control of the loose dog 16 at the time.

70 In Figs. 7 and 8 I have illustrated a modification of my invention which performs some, but not all, of the functions of the form shown in Figs. 1-6. In this simpler 80 form of the invention the margin dog 50 has a tooth 49 adapted to engage the "zero" tooth 27 of the escapement wheel in the same manner as the dog 25 of the other form, and said dog 50 also has a depending ear 51 85 adapted to be struck by the screw 41 to move the dog out of engagement. The dog 50, like the dog 25, is of bell crank form having a forwardly directed arm 52 having frictional connection with the carriage, the frictional contact in this instance, however, being not with the rack 10 but with the tape 12. The arm 52 extends beneath said tape in such position as to bend the tape upward enough to produce the desired friction. In 90 this instance the dog 50 is staked on a hub 53 which is pivoted on a stud screw 54 screwed into a base plate 55 which is secured to the top plate by screws 56 and made adjustable in the same manner as the base 100 plate 30 by elongating the holes through which the screws 56 pass. A stop pin 57 is provided similar to the pin 35. In these 105 Figs. 7 and 8 I have shown a different form of detent consisting of a light spring 60 lying on the top plate 1 and having its free end in position to engage the tooth 27 next behind the "zero" tooth of the escapement wheel. This is a well-known form of detent and is here shown provided as usual 110 with a guard 61 consisting of a stiffer piece of sheet metal lying on top of the detent 60 for the greater part of its length. This guard and detent are here shown as secured to the top plate 1 by the same screws 56 as 115 the plate 55, said plate 55 being mounted on top of the guard 61.

120 It will be perceived that this form of the margin dog is not provided with any spring like the spring 34 but is moved into engagement with the escapement wheel by the friction of the band 12 when the carriage is moved toward the operator's right. It is thrown out of engagement at the first operation of the dog rocker by the screw 41 acting 125 on the ear 51 and it is retained out of action by the friction of the band 12, as well as by the fact that there is nothing in particular to cause it to come back into action. In this form of the invention it will 130

be perceived that the margin dog engages the wheel whenever the carriage is moving toward the right whether or not said carriage is released by raising the feed rack 10. 5 This form of the invention is effective to cure the faults found with the left-hand margin of the writing and in all other instances where the carriage is actually moved backward toward the right by any means; 10 but it is not effective when the carriage is moved toward the operator's left, that is to say, in letter feed direction, when said carriage is released from the escapement mechanism as for example in an ordinary tabulating operation. In this respect and perhaps in other respects the first form of the 15 invention is superior to this one.

In order to make the relation of my improved mechanism to the remainder of the 20 machine more apparent I have illustrated in Fig. 9 some of the parts of one form of typewriting machine in which my invention is shown embodied. In this machine the top plate 1 is supported on corner posts 64 25 rising from a frame base 65. The carriage 9 is supported by ball bearings on rails 66 mounted on the top plate 1. At each end of said carriage a release key lever 67 is pivoted on a screw 68, the key 70 being at 30 the forward end of said lever and the rear end of the lever lying beneath the feed rack 10, which feed rack is mounted on arms pivoted to the carriage but which arms do not show in the drawing. The carriage and 35 its appurtenances shown are of the kind heretofore used in the Remington machine. A margin stop 71 is mounted on a bar 72 at the front of the carriage and it is adjustable in a right and left-hand direction by 40 means of a handle 73. The stop 71 shown in the drawing is the left-hand margin stop which defines the left-hand edge of the paper and at the right side of the carriage is a similar stop which controls the line 45 lock mechanism. Both of said stops coöperate with a stationary stop 74 pivoted at 75 to the forward rail 66 at the middle of said rail.

The machine is shown equipped with a 50 column selecting tabulator comprising a column stop bar 76 mounted on arms 77 projecting upward and rearward from the carriage. Several column stops 78 are mounted on the bar 76 and adjustable along 55 it in the usual way, the column stops here shown having stop lugs or projections 80 at various heights for coöperation with key operated stops contained within a casing or frame 81 secured at 82 to the top plate and 60 at 83 to the base of the machine. The frame 81 contains a series of upright levers 84 of the first order pivoted at 85, the lower forwardly projecting ends of said levers being pivoted to the rear ends of horizontal links 65 86 which at their forward ends are pivoted

to levers 87 which levers are fulcrumed on a transverse rod or shaft 88 in the base 65. The levers 87 are operated by sliding keys 90 at the back of the keyboard. At its upper part the frame or casing 81 contains 70 stop mechanism such as is shown in my patent No. 1,132,286 granted March 16, 1916. As is fully explained in said patent this stop mechanism is capable of arresting the carriage when the latter is traveling 75 either toward the left in letter feed direction or toward the right.

Whenever one of the keys 90 is pressed the carriage is released from the escapement, the means for this purpose comprising 80 a universal bar 91 mounted by means of arms 92 on the rod or shaft 88 in such position that said universal bar is pushed toward the rear every time one of the levers 87 is operated. Said universal bar is connected by means of links 93, one at each end thereof, with arms 94 depending from a rock shaft 95 mounted in brackets 96 in the base part 65. At near its middle said rock shaft has another arm 97 which is connected by means of a long link 98 with the rear end of a lever 100 of the first order pivoted on top of the top plate 1 and having its forward end beneath the rack 10. The construction is such that the rear end of 95 said lever is pulled downward when a tabulator key is operated and its forward end lifts the rack 10 out of the pinion 7. I have not deemed it necessary to bring out all of the details of this mechanism in this 100 drawing because they are well known in the art and are shown in my patent above referred to; and in practice this lever 100 carries a retarder device through which the feed rack is lifted as in the regular Reming- 105 ton machine.

The carriage can be moved backward one letter space position at a time by means of a back spacing key 101, the key lever 102 of which is pivoted at the rear of the machine 110 on a pivot rod 103 which rod also serves as a pivot for the printing key levers; and the lever 102 is normally held up by a spring 104 connected at its upper end to a cross bar 105 which cross bar also carries similar 115 springs connected with the printing key levers. The lever 102 is connected by means of a link 106 with an arm 107 projecting from a rock shaft 108 journaled in the upper part of the machine and having projecting rearward therefrom another arm 110 with the rear end of which are connected certain certain devices 111 terminating in a back spacer pawl 112 which pawl takes hold of the ratchet wheel 8 and turns it in the 120 direction the reverse of its letter feed direction, thus moving the carriage backward or toward the right through the instrumentality of the pinion 7 and rack 10. This back spacer mechanism is fully shown and 130

described in the patent to E. E. Barney, No. 1,270,918, granted July 2, 1918.

The printing mechanism includes front strike type bars 113 pivoted to a segment 114 and connected in any suitable way with printing key levers not shown. All of said type bars however operate a segmental universal bar 115 having arms 116 projecting therefrom toward the rear of the machine, 10 their rear ends being supported by arms 117 rising from a rock shaft pivoted at 118 to brackets 120 depending from the top plate 1. A link 121 is connected with one of the arms 117 and extends thence toward the 15 rear of the machine where it is connected with one of the pins or studs 21 on the dog rocker arm 22. The details of this universal bar construction and its connections with the dog rocker are all more fully shown in my 20 prior application Serial No. 118,607, herein-before referred to.

A space bar 122 may be mounted in any suitable way and connected with the dog rocker by any suitable means.

25 The line lock mechanism includes a channel bar 123, adapted to engage and lock a hook 124 on the back spacer key lever 102, and similar hooks on the printing key levers. The locking bar 123 is pivoted at 125; and 30 at its left-hand end has an arm 126 from which a link 127 rises, said link being controlled, through connections not shown, by a transverse sliding motion of the stop 74.

It is new as far as I am aware to provide 35 a margin dog with means whereby it is thrown out of action by the operation of the printing keys or a space key and with means whereby it continues out of action during the operation of writing and comes into action 40 again only when it may be needed. In this respect my device works according to a new mode of operation and a new principle and it is therefore my intention to claim this improvement broadly.

45 It is believed that a better or clearer understanding of the scope of my improvements will be had by describing now more in detail the important features thereof and their peculiar functions or modes of operation under the varying conditions which 50 from time to time arise in the operation of the typewriter.

The dog carrier or rocker is always free 55 to be rocked or vibrated, whether the carriage is in transit back or forth. Hence every time a letter key or the space key is operated the dog carrier is moved and the stepping dog passes out of engagement with the escapement wheel and steps to the left 60 while said wheel is held by the rigid dog. If this action should take place while the carriage is arrested in its leftward travel or if it should take place during a retraction of the carriage, a letter space would be lost 65 when the carriage is arrested at the end of

its rightward travel but for the presence of my improvements, because eventually in either instance the stepping dog will return to the wheel in a one-tooth advanced position. Hence when the carriage return movement has ceased and the spring drum is again effective to exert its propelling power on the carriage the feed rack, the feed pinion and the escapement wheel will move and the stepping dog will be carried back by the 70 wheel to normal position against its right-hand stop, thus permitting the carriage to move one false step and which, as before explained, is productive of an uneven margin on the left-hand side of the sheet of writing. 75

More specifically, assuming that the carriage has traveled its full distance to the left and has been arrested by the stationary stop, if then a key be struck and, owing to failure of the line lock to function properly, 80 the dog rocker be vibrated the loose or stepping dog will be disengaged from the escapement wheel and will make its leftward step as usual; but owing to the engagement of the carriage with the margin stop there 85 will be no stepping of the carriage at this time. Immediately, however, the retraction of the carriage is started the margin dog or hook is caused to engage with a tooth of the escapement wheel and thus hold it from 90 moving or stepping as long as this margin dog or hook is engaged with said wheel, and it will remain thus in engagement until a 95 letter key or space key is again struck. Hence when the carriage is fully retracted 100 and arrested by its margin stop and the carriage spring is again free to exert its influence the carriage is unable to make the false step referred to by reason of the fact that the margin dog is still holding the escapement wheel against rotation; and at this time it will be noted that the stepping dog is over against its left-hand stop and ready 105 to be vibrated against its right-hand stop the moment the escapement wheel is permitted to rotate. Thus it will be seen that when the returned carriage is brought back against its margin stop, which for example we may say is set at "5" on the scale, the carriage will be arrested at "5" and the 110 next letter printed will take place at "5" instead of at "6" as would be the case were it not for the margin dog; though the stepping dog is out of its normal holding position.

The first key struck at "5" will vibrate the 115 always free rocker and this movement of the rocker will force or kick back the margin dog or hook, and thus allow the escapement wheel to turn upon relief of the type key from pressure, this turning of the wheel 120 permitting the stepping dog to be brought up against its right-hand stop again and permitting also the feed pinion, the rack and the carriage to move one step in printing direction. Thereafter until another retractive 125 130

movement of the carriage is made the margin dog will remain quiescent. However, the hook or margin dog is adapted to engage with the escapement wheel and hold it, and through it the rack, the pinion and the carriage, from making a false step whenever the rack and pinion may be separated, either by an operation of the carriage release key or by an operation of any tabulator key.

10 The moment such a rack-and-pinion separation occurs the margin dog is caused automatically to engage a tooth of the escapement wheel and hold it in substantially the same way that it does when the carriage is retracted without separating the rack and pinion. The margin dog in both instances referred to is caused to engage a tooth of the escapement wheel by the action or recoil of the spring 34, which is prevented normally from causing the margin dog thus to act by the friction of the carriage rack on one arm of the pivoted margin dog device, this friction having at all times, excepting when the carriage is being returned, a tendency to force or hold said friction arm in the direction of the letter feed movement of the carriage, and this tendency or action serves to maintain the hooked or margin dog arm of the device in forward or non-operative position.

20 As soon, however, as the friction operates in the opposite direction by the return push or pull of the carriage, then the spring is free to operate immediately upon the margin dog and swing it rearwardly so as to engage the operative face of one of the teeth of the escapement wheel and thus hold it indefinitely or until the next vibratory movement of the dog rocker is effected by a subsequent action of one of the type keys or the space key. Of course when the feed rack is raised there is then no friction upon the margin dog device to hold it in inoperative position and then the spring acts immediately to move the hooked end of the device into engagement with the escapement wheel, and there it will remain even though the rack and pinion be reengaged until the dog rocker is again vibrated as by striking the space key or one of the letter keys.

30 From the foregoing it will be understood that when the margin dog is out of engagement with the escapement wheel it is maintained in this condition against the tension of its spring by the superior force of the friction between the carriage moving part and a part of the margin dog holding device, and that once the spring has been permitted to act, the margin dog cannot be restored to non-operative position by friction between the said parts but only by a positive movement of the dog carrier, and that when that takes place the aforesaid friction may again predominate and the margin dog will be held

40 out of service until the friction is either

wholly removed or reduced in power below that of the tension of the spring. In the immediately preceding description it will be understood that some of the modes of operation or functions performed do not take place in that modification of my invention shown in Figs. 7 and 8 where the carriage strap or tape is used to obtain the friction for the margin dog instead of the rack as in other figures, and for this reason the construction shown in Figs. 1 to 6 inclusive and Fig. 9 is the preferred construction.

Various changes may be made in the details of construction and arrangement without departing from my invention.

What I claim as new and desire to secure by Letters Patent, is:

1. In a typewriting machine and in carriage controlling mechanism, the combination with an escapement wheel and key controlled feed dogs co-operating therewith, of a third dog for engaging and holding said wheel against stepping, and means for maintaining said third dog out of action during the operation of writing.

2. In a typewriting machine and in carriage controlling mechanism, the combination with an escapement wheel and vibratory means for controlling the step by step rotation of said wheel, of a margin dog for engagement with said wheel to hold the latter against stepping, said margin dog being moved out of engagement with said wheel by said vibratory means, and means for maintaining said margin dog out of action during the operation of writing.

3. In a typewriting machine and in carriage controlling mechanism, the combination with an escapement wheel and vibratory means for controlling the step by step rotation of said wheel, of a margin dog for engagement with said wheel to hold the latter against stepping, said margin dog being moved out of engagement with said wheel by said vibratory means, and means for maintaining said margin dog out of action during the operation of writing and for bringing said dog into action during the return motion of the carriage.

4. In a typewriting machine and in carriage controlling mechanism, the combination with an escapement wheel, vibratory means for controlling the step by step rotation of said wheel and a carriage release mechanism, of a margin dog capable of holding said wheel against the force of the carriage spring in case of a false operation of said vibratory means, said dog being moved out of engagement with said wheel by said vibratory means, and means for moving said dog into engagement with said wheel when said carriage release mechanism is operated.

5. In a typewriting machine and in carriage controlling mechanism, the combination with escapement mechanism and car-

riage release mechanism, of a margin dog capable of holding the carriage against the force of its driving spring in case of a false operation of said escapement mechanism, 5 and means whereby said margin dog is brought into action by an operation of said carriage release mechanism.

6. In a typewriting machine and in carriage controlling mechanism, the combination 10 with an escapement mechanism and carriage release mechanism, of a margin dog capable of holding the carriage against the force of its driving spring in case of a false operation of said escapement mechanism, 15 means whereby said margin dog is brought into action by an operation of said carriage release mechanism, and means whereby an operation of said escapement mechanism throws said margin dog out of action.

20 7. In a typewriting machine and in carriage controlling mechanism, the combination with carriage escapement mechanism, of a margin dog, means whereby said margin dog is thrown out of action by an operation of said carriage escapement mechanism, and means whereby said margin dog is brought into action by the act of restoring the carriage toward the right.

30 8. In a typewriting machine and in carriage controlling mechanism, the combination with carriage feed mechanism including a releasable feed rack, of a margin dog having frictional connection with said rack, such frictional connection being broken by 35 the act of releasing said rack.

35 9. In a typewriting machine and in carriage controlling mechanism, the combination with carriage escapement mechanism and carriage release mechanism, of a margin dog, means whereby an operation of said carriage escapement mechanism throws said margin dog out of action; and means whereby the return motion of the carriage and also an operation of said carriage release mechanism throws said margin dog into action.

40 10. In a typewriting machine and in carriage controlling mechanism, the combination with carriage escapement mechanism and carriage release mechanism, of a margin dog, frictional means for maintaining said dog out of action during the letter feed movement of the carriage, and spring means for moving said dog into action when said 45 carriage release mechanism is operated.

45 11. In a typewriting machine and in carriage controlling mechanism, the combination with escapement mechanism and a feed rack, of a bell crank, one arm of said bell 50 crank having frictional connection with said feed rack, and the other arm acting as a margin dog, and means whereby said margin dog is thrown out of action by an operation of said escapement mechanism.

55 12. In a typewriting machine and in car-

riage controlling mechanism, the combination with escapement mechanism, of a margin dog for holding the carriage against the force of its driving spring, said margin dog having frictional connection with the carriage; and means whereby said margin dog is moved out of holding position by an operation of said escapement mechanism. 70

13. In a typewriting machine and in carriage controlling mechanism, the combination 75 of means for holding said carriage against stepping, key actuated means for moving said holding means to release the carriage therefrom, and means including frictional connection with the carriage for 80 retaining said holding means out of holding position.

14. In a typewriting machine and in carriage controlling mechanism, the combination with a carriage, an escapement wheel 85 and feed dogs for controlling the said wheel, of a margin dog in the form of a bell crank, one arm of said bell crank adapted for engagement with said wheel and the other arm having frictional connection with the carriage; and means whereby an operation of 90 said feed dogs moves said margin dog out of engagement with said wheel.

15. In a typewriting machine and in an escapement mechanism, the combination of 95 a carriage, a releasable feed rack, a margin dog, and means for enabling the margin dog automatically to engage the escapement mechanism whenever the rack is released and to maintain its said engagement after 100 the rack is restored to normal position.

16. In a typewriting machine and in an escapement mechanism, the combination of 105 a carriage, a releasable feed rack, a margin dog, and a spring for causing the margin dog automatically to engage the escapement mechanism whenever the rack is released and to maintain its said engagement after the rack is restored to normal position.

17. In a typewriting machine and in an 110 escapement mechanism, the combination of a carriage, a releasable feed rack, a margin dog, a spring for causing the margin dog automatically to engage the escapement mechanism whenever the rack is released, 115 and friction devices for holding said margin dog non-engaged when the rack is in working position.

18. In a typewriting machine and in an escapement mechanism, the combination of 120 a carriage, a releasable feed rack, a margin dog, a spring for causing said margin dog automatically to engage the escapement mechanism whenever the rack is released, means carried by the escapement mechanism 125 for disengaging said margin dog whenever a key is operated, and friction means connected with a moving part of the carriage for holding said margin dog normally disengaged. 130

19. In a typewriting machine and in an escapement mechanism, the combination of a carriage, a margin dog, friction devices for holding said margin dog in normal non-operative position, and a spring for causing said margin dog to move to operative position when said friction is removed or reduced.
20. In a typewriting machine and in an escapement mechanism, the combination of a carriage, a margin dog, friction devices connected with the carriage for keeping said margin dog normally in non-operative position, and a spring for throwing said dog into operative position during a retractive movement of the carriage.
21. In a typewriting machine, the combination with an escapement mechanism comprising an escapement wheel, a stepping dog and a holding dog, of a margin dog normally quiescent but adapted to move and hold the escapement wheel after the stepping dog has made a false step and to maintain said hold on said wheel until a space key or character key is operated.
22. In a typewriting machine, the combination with an escapement mechanism comprising an escapement wheel, a stepping dog and a holding dog, of a normally quiescent margin dog adapted to move and engage and hold said escapement wheel until and after the carriage has been arrested in its return stroke, and means connected with the keyboard for restoring said margin dog to normal position.
23. In a typewriting machine, the combination with an escapement mechanism comprising an escapement wheel, a stepping dog and a holding dog, of a normally quiescent margin dog adapted to be moved into engagement with said wheel and hold it at the commencement of the retractive movement of the carriage and to maintain its hold on said wheel after the retractive movement of the carriage has entirely ceased and is in condition again to commence its forward or leftward movement by operating the printing keys.
24. In a typewriting machine, the combination of an escapement mechanism comprising an escapement wheel, a dog rocker

carrying a stepping dog, and a normally quiescent margin dog adapted to be moved to engage said wheel without interfering with the free vibration of said dog rocker whereby said wheel and the carriage are held from thus making a false step although the stepping dog may be caused to make such a step.

25. In a typewriting machine, the combination of a carriage, an escapement mechanism comprising an escapement wheel, a dog rocker carrying a stepping dog, said rocker being free to be vibrated after the forward movement of the carriage has been arrested by its margin stop, whereby said stepping dog may be moved to a false position, a margin dog caused to engage said wheel immediately the carriage is started to the right and to hold said wheel against turning until a character has been printed, whereby the error which would have been occasioned by the false stepping of the stepping dog is corrected by the holding of the escapement wheel.

26. The combination with an escapement wheel and two coöperating feed dogs, one of which is a stepping dog capable of assuming a false position, of a third dog normally inactive but adapted to take the place of said stepping dog, means for moving said third dog into action when the carriage is retracted, and means for moving said third dog out of action at the next succeeding operation of a character key or space key.

27. The combination with a carriage, an escapement mechanism, and a releasable feed rack, of a dog capable of holding the carriage against stepping motion, means whereby said dog is normally held out of action by said feed rack, and means whereby said dog, when in action, is thrown out of action by an operation of said escapement mechanism.

Signed at Ilion, in the county of Herkimer and State of New York, this 2nd day of December, A. D. 1918.

GEORGE A. SEIB.
